UNITED STATES PATENT OFFICE.

CECIL F. ADAMSON, OF EAST PALESTINE, OHIO, ASSIGNOR OF ONE-HALF TO WALTER GROTE, OF EAST PALESTINE, OHIO.

DESIGN FOR A FLAG OR EMBLEM.

52,202.

Specification for Design.

Patented July 23, 1918.

Application filed April 23, 1918. Serial No. 230,347. Term of patent 7 years.

To all whom it may concern:

Be it known that I, CECIL F. ADAMSON, a citizen of the United States, residing at East Palestine, county of Columbiana, and State of Ohio, have invented a new, original, and ornamental Design for a Flag or Emblem, of which the following is a specification, reference being had to the accompanying drawing, in which:—

The figure is a plan view of a flag or emblem embodying the invention.

I claim:—

The ornamental design for a flag or emblem, as shown.

CECIL F. ADAMSON.

Witnesses:

B. A. UNGER,
G. L. BICKMYER.
